Primary Examiner — Angela J Lee(74) *Attorney, Agent, or Firm* — K&L Gates LLP(57) **CLAIM**

The ornamental design for a recessed lighting fixture, as shown and described herein.

DESCRIPTION

FIG. 1 illustrates view of the front side of a recessed lighting fixture.

FIG. 2 illustrates a cross-sectional view of the recessed lighting fixture.

FIG. 3 illustrates a perspective view of the recessed lighting fixture and includes a cut plane that is indicative of the cross-sectional view of FIG. 2.

FIG. 4 illustrates a bottom-up, view of the recessed lighting fixture; and,

FIG. 5 illustrates a perspective view of a top side of the recessed lighting fixture.

In the drawings, the broken lines represent portions of the recessed lighting fixture that form no part of the claimed design.
